UNITED STATES PATENT OFFICE.

FREDERICK GEOFFREY LEES JOHNSON, OF WESTMINSTER, ENGLAND, ASSIGNOR TO
VICKERS LIMITED, OF WESTMINSTER, ENGLAND.

VENT-SEALING PERCUSSION-PRIMER.

1,400,554.

Specification of Letters Patent. Patented Dec. 20, 1921.

Application filed May 14, 1919. Serial No. 297,151.

(GRANTED UNDER THE PROVISIONS OF THE ACT OF MARCH 3, 1921, 41 STAT. L., 1313.)

To all whom it may concern:

Be it known that I, FREDERICK GEOFFREY LEES JOHNSON, a subject of the King of Great Britain, residing at Vickers House, 5 Broadway, Westminster, in the county of London, England, have invented certain new and Useful Vent-Sealing Percussion-Primers, for which I have filed an application in Great Britain, Jan. 24, 1918, Patent 10 #130,096, and of which the following is a specification.

This invention relates to vent sealing percussion tubes or primers of the ball and conical seating type and has for its chief 15 object to effect the sealing of the tube before any gas pressure from the magazine, which is necessary to actuate the usual ball seal, can be effective.

According to this invention a charge of 20 fulminate or detonating composition through which the magazine is fired is associated with a sealing pellet, preferably of copper, adapted on ignition of the said composition to be driven against the conical seating to 25 form a seal, without depending on the gas pressure due to the ignition of the magazine.

In order that the said invention may be 30 clearly understood and readily carried into effect, we will now describe the same more fully with reference to the accompanying drawings, in which:—

Figure 1 is a longitudinal section of a 35 vent sealing tube embodying this invention; and

Fig. 2 is a detail view showing a slight modification.

A is the vent sealing tube body having at 40 one end a magazine *a* filled with gunpowder. B is the screw plug at the rear end of the powder chamber or magazine, provided with a tubular nipple *b*. C is the conical chamber inside the tube body. D is the copper sealing pellet fitting over the end of the nipple *b*. E is the percussion 45 cap.

The tubular nipple or extension *b* forms a recess receiving the fulminate or detonator charge *b'* which may if desired be separated from the flash passage *b²* leading to the 50 powder charge in the chamber *a* by a thin copper disk or diaphragm at *b^x*.

The copper sealing pellet *D* fits over the end of the nipple *b* as a cap and the rounded part of the pellet faces the contracting por-

tion of the conical chamber C, through 55 which is led the flash from the percussion cap E in the base of the tube A, igniting the fulminate or detonating charge *b'* through small openings *b³* at the base of the nipple below the pellet cap. At the apex 60 of the conical chamber flash passages *a'* lead to the percussion cap E.

On firing the percussion cap E the flash passes from the cap through the conical chamber C, igniting the fulminate or detonating charge *b'* at the nipple *b*, the action 65 of the explosion of the charge driving off the sealing pellet D and forcing it into the conical seating of the chamber C, so as to close the tube or primer completely. At 70 practically the same moment, the powder charge in the magazine *a* is ignited by the flash from the detonating composition. The detonating charge acts as an augmentor to the flash given by the percussion cap E, 75 thus assisting the ignition of the powder charge.

In a slight modification shown in Fig. 2 the pellet D is not fitted closely on the 80 end of the nipple *b* but is separated from the end by a small auxiliary charge *b⁴* of the detonating composition separated from the initial charge *b⁵* by the length of the nipple. In this case the charge *b⁵* is first 85 fired by the flash from the percussion cap and the flash then passes through the central passage of the nipple back to the auxiliary charge *b⁴*. This insures the effective action 90 of the pellet since it expands the pellet as it drives it off the nipple into the conical recess.

What I claim and desire to secure by Letters Patent of the United States is:—

1. In a vent sealing percussion primer, a 95 primer body provided with a flash passage and a conical chamber forming a seating, a magazine charge, a member closing the end of the magazine chamber and provided with a passage leading from the conical chamber to the magazine chamber, a small 100 detonating charge placed within the said passage and separated from but communicating with the magazine charge, and a sealing pellet at the rear end of the said passage which pellet is adapted to be driven 105 into the conical seating by the pressure due to ignition of the said detonating charge in front, for the purpose specified.

2. In a vent sealing percussion primer, a primer body provided with a flash passage and a conical chamber forming a seating, a magazine charge, a plug closing the end 5 of the magazine chamber, a tubular nipple on the plug, a charge of detonating composition carried by the plug and a sealing pellet

covering the end of the said tubular nipple and adapted to be driven into the conical seating by the explosion of the detonating 10 charge, for the purpose specified.

In testimony whereof I affix my signature.

FREDERICK GEOFFREY LEES JOHNSON.
